Attorney.

UNITED STATES PATENT OFFICE.

WILLIAM T. HANNA, OF CINCINNATI, OHIO.

MECHANICAL STOKER.

Application filed July 5, 1919. Serial No. 308,851.

To all whom it may concern:

Be it known that I, WILLIAM T. HANNA, a citizen of the United States of America, and a resident of Cincinnati, in the county 5 of Hamilton and State of Ohio, have invented a new and useful Improvement in Mechanical Stokers, of which the following is a specification.

My invention relates to a class of mechanical stokers which are particularly adapted for use in stoking locomotive engines.

The object of my invention is to provide a stoker which when in position does 15 not interfere with free access to the furnace opening, so that hand stoking may be resorted to readily.

Another object of my invention is to provide an improved means for mounting 20 the fuel conveyors.

These and other objects are attained by the means described in the specification and illustrated in the accompanying drawings, in which:—

25 Fig. 1 is a rear elevation of a mechanical stoker embodying my invention.

Fig. 2 is a side view thereof upon a somewhat enlarged scale.

30 Fig. 3 is a view partly in section and partly in elevation, and upon an enlarged scale of the manually operated means for connecting and disconnecting the guide wings from their operating shafts.

Fig. 4 is a detail rear elevation of the 35 furnace opening and of the wings in their inoperative position.

Fig. 5 is a sectional detail view taken upon line 5—5 of Fig. 3.

40 Centrally located beneath the furnace-door-opening A, is an inclined feed tube B to the mouth of which is secured a casing b within which casing is revolvably mounted a suitable spiral screw b¹, whereby fuel may be conveyed from a fuel reservoir, not shown, to and thru the feed tube B. The casing b and screw b¹ together with the tube B constitute a primary feeding and elevating conveyor, discharging into an intermediate conveyor comprising 45 the casing D.

At its upper end feed tube B is coupled centrally to and communicates with a secondary casing D which is secured to the rear wall of the engine boiler in a horizontal 55 position beneath the furnace-door-opening or primary firing opening A. The casing

D and the spiral screws therein contained, constitute a horizontal or intermediate conveyor. At the ends of the casing D, inclined fuel conduits E, E¹, enter the sides 60 of a casing a which surrounds the furnace door or primary firing opening A and has in its rear wall an opening A¹ in substantial horizontal alignment with the opening in the furnace wall. The forward wall of the casing a is provided with suitable flanges a¹⁰⁰ whereby the casing may be secured to the boiler wall. The forward wall of the casing a has an aperture which registers with the primary firing opening, or if desired, the forward wall may be dispensed with, the objective being 65 the provision of a chamber between the rear wall of the casing a and the rear wall of the fire box or boiler, in which chamber the distributing wings may be oscillated and thru which chamber unobstructed access 70 may be had to the primary firing opening whereby to permit hand firing without removal or displacement of any of the stoker mechanism. At the junctures of the fuel conduits E, E¹ with the casing D, there are formed journal bearings d, d¹ in which are journaled a horizontal shaft d² and the lower ends of the shafts of screws e, e¹. Shaft d² has mounted upon it spiral blades d³, d⁴, of opposite spirality. The shafts carrying the screws e, e¹ are connected by bevel gears to the shaft d² which carries 75 a pinion d⁵ which is connected with an actuating mechanism not shown.

In the walls of casing a, above the primary and secondary firing openings A and A¹, are revolvably mounted longitudinal stub shafts g, g¹, upon which are secured distributing wings or chutes G, G¹ which normally are in position to receive fuel discharged from the upper ends of conduits E, E¹, and to direct and discharge it upon the distributing plate h¹ and ejector h², extending into the primary firing opening A. The conduits E and E¹ contain revolvable spiral screws e and e¹ respectively, and constitute secondary elevating conveyors communicating at their lower ends with the intermediate conveyor, and converging toward their tops where they discharge into the guide wings G and G¹, which distribute the fuel upon the distributing plate.

The means for manually connecting and disconnecting the distributing wings from their operating mechanism H, is as fol-

lows:—Upon each of the shafts g , g' a sleeve g^2 is secured, which has an upwardly projecting arm g^3 , upon which is pivoted a handle g^4 , which has a lug g^5 which is 5 adapted to engage a notch in an arm g^6 which projects upwardly from a sleeve g^7 which is mounted loosely upon the stub shaft g . Sleeves g^7 have arms g^8 which are connected by links g^9 with the operating mechanism H . This operating mechanism is 10 described in Reissue Letters Patent No. 14,179, re-issued Aug. 8, 1916, for a mechanical stoker of my invention, and need not therefore be more specifically described herein. The device H is adapted to control the 15 operation of the wings G and G' and comprises a suitable reciprocating rod h to which links g^9 are pivotally connected. As the reciprocating rod h is actuated, the reciprocating motion thereof is translated into an oscillating motion of the wings about their respective pivotal mountings, whereby the wings direct fuel from the elevating conveyors comprising conduits E and E' , and 20 screws e and e' , to the distributing plate h^1 and ejector h^2 .

Upon the sides of the furnace are secured plates g^{10} , g^{11} , which have in them notches which are adapted to be engaged by the lugs 30 g^5 of the handles g^4 , when the wings G , G' are brought into their inoperative positions such as shown in Fig. 4, so as to hold the wings clear of the passage leading from the furnace door opening to the fire box.

In operation fuel is carried thru the primary conveyor and is forced by incoming fuel upward into the casing D . The spiral blades d^3 , d^4 convey the fuel to the conduits E , E' , the screws e , e' carry it upward and it 35 is discharged onto the distributing wings G , G' which in their oscillation distribute it upon the distributing plate to be conveyed thence by a suitable ejector into the fire box.

The operation of rendering each of the 40 wings or chutes G , G' inoperative, and swinging them free of the passage extending between the primary and secondary firing openings is as follows:—Lugs g^5 are 45 released from the notches in their respective

arms g^6 by grasping handles g^4 and swinging them around their pivots. The wings are then manually rotated about their respective shafts g and g' . When the wings have been swung to positions free of the 50 passage, they are locked in position by lodging the lugs g^5 in slots in the plates g^{10} and g^{11} . In this position of the wings the furnace door opening is unobstructed so that hand stoking may be readily resorted to.

Although the casing a , casing D , and feed 60 tubes E and E' are shown and referred to as separate elements, it is readily apparent that they may be formed integral, whereby to form a single composite housing within which the several operating mechanisms are 65 contained. As shown, the several referred to parts are for all purposes to be considered as a single housing.

Having thus described my invention, 70 what I claim is:

1. In a mechanical stoker for a furnace having a furnace door opening, the combination of a horizontal conveyer disposed below the furnace door opening adapted to move fuel towards its opposite ends, upwardly converging conveyers communicating with the ends of the first mentioned conveyer terminating adjacent the sides of the furnace door opening, and means directing the fuel from the second mentioned convey- 75 ers to the firing door opening.

2. The combination with a furnace having a firing opening in its wall, of a housing mounted upon the exterior of the wall embracing the opening, said housing having a 80 wall spaced from the furnace, said wall having a firing opening in alignment and registering with the firing opening of the furnace, and a distributer in the housing adapted to operate across the passage between 85 the two firing openings, and to assume an inoperative position withdrawn from said passage.

In testimony whereof, I have hereunto 90 subscribed my name this 3rd day of July, 1919.

WILLIAM T. HANNA.
